1 Claim. (Cl. 62—514)

ABSTRACT OF THE DISCLOSURE

A heater is included in the uninsulated, flexible-transfer-line cooling system of a cryogenic system, the heater being inserted at the exhaust port of the supply dewar to extend the cooling capability of the system.

This invention relates to cryogenic cooling systems and especially to cryogenic cooling systems which employ flexible transfer lines.

Uninsulated flexible-transfer-line cryogenic cooling systems, such as are used for the cooling of infra-red vidicon camera tubes, presently are limited to cooling loads of up to approximately two watts. These systems generally consist of a vacuum-insulated supply dewar vessel, some means for system pressure build-up such as a pressure build-up coil or a pressure-activated heater, a cell dewar vessel into which the load which is to be cooled is inserted, a flexible transfer line, such as silicone rubber tubing, through which the coolant is transferred from the supply dewar to the cell dewar, and the necessary pressure and flow control valves.

The successful operation of an uninsulated, flexible-transfer-line cryogenic cooling system depends on the maintenance of stable two-phase flow in which the liquid phase, in the form of drops, is transferred through the transfer line by the vapor phase. The flow regime must be such that the vapor forms a superheated insulating layer of vapor around the inside wall of the transfer line thereby simultaneously insuring line flexibility and minimizing the evaporation rate of the liquid drops.

The required two-phase flow regime in low wattage systems is maintained by heat absorption from the environment. At higher cooling loads and at higher flow rates, the heat absorbed from the environment is insufficient for the maintenance of the required two-phase flow regime. Under such conditions, the transfer tube wall is gradually cooled down until it reaches a critical temperature at which a liquid film is formed along the inside surface changing the flow regime to annular flow which is characterized by a high heat transfer coefficient. This is followed by a step increase in heat absorption from the environment and the sudden loss of flexibility of the rubber transfer tube. The system becomes completely inoperative under such conditions, not only because of loss of tube flexibility, but also because the increased heat transfer along the tube results in excessive evaporation of the liquid with the resultant reduction of the cooling efficiency of the system to an impractical value.

The present invention extends the cooling capability of this type of cryogenic system at least one order of magnitude by the insertion of a high-intensity heater at the exhaust port of the supply dewar vessel. The necessary heater power is a function of the mass flow rate of the coolant.

An object of this invention is to maintain stable-two-phase flow in uninsulated, flexible-transfer-line cryogenic systems.

Another object is to maintain stable two-phase flow in uninsulated, flexible-transfer-line cryogenic systems where the

2

the cooling load is in excess of approximately two watts.

Other objects and many of the attendant advantages of this invention will be readily appreciated as the same becomes better understood by reference to the following detailed description when considered in connection with the accompanying drawings wherein:

FIG. 1 is a schematic illustrating a cryogenic cooling system utilizing the present invention;

FIG. 2 is a curve showing required minimum heater exit qualities for a range of flow rates; and

FIG. 3 is a side view cross-section taken through the heater element block.

FIG. 1 illustrates a cryogenic cooling system which can be used to cool an IR vidicon camera tube. The system 15 comprises a vacuum-insulated supply dewar 12 and a vacuum-insulated cell dewar 14 connected by means of a flexible transfer tube 16 which may be fabricated from silicone rubber tubing. The vessels are employed to hold liquid nitrogen. The tubing 18 at the exhaust port of the supply dewar 12 is encased by a heater element 20 consisting of a metallic block, such as copper, containing an electric heating element therein.

The cell dewar 12 (or load dewar vessel) may be employed to hold the cooling finger 22 of an infra-red vidicon camera tube which is to be cooled.

The remainder of the system comprises the vapor return line 26 and a suitable pressure-regulating means which may, for example, consist of an absolute pressure regulator valve 28 with a vapor discharge port, a pressure regulator 30, a pressure build-up coil 32, a solenoid valve 34, a relief valve 36, a manual relief valve 38, a check valve 40 and a fill fitting 42.

Different types of heater elements may be employed. One type consists of a commercial electrical heater $\frac{3}{8}$ -inch 35 in diameter and $1\frac{1}{2}$ inches long, rated at 40 watts for a 28 volt source, inserted inside a copper block which encloses the exhaust-port tubing of the supply dewar. The copper block is insulated with glass wool insulation to minimize heat loss to the environment.

40 A side view cross-section of the heater element block 44 is shown in FIG. 3. The block 44 consists of two halves which are screwed or bolted together. Two holes are bored through the block, one 46 to hold a cylindrical electrical heater and the other 48 to enclose the tubing 45 from the exhaust port of the supply dewar.

Proper operation of any heater element requires that the heat flux (power per unit area) be sufficiently high to ensure film boiling in the heater section. Of course, a good thermal path is desirable to minimize heat losses.

50 Control of heater power as a function of mass flow rate is necessary in order to maintain the desired two-phase flow regime. If sufficient heat is not provided, the flow regime, and consequently the system performance, becomes time dependent, the transfer tube temperature 55 dropping with time until a critical temperature is reached, when a sudden drop in temperature occurs. With sufficient heater power, or with sufficiently high heater exit quality, this breakdown does not occur but steady-state continuous operation is obtained. There exists a minimum heater power for a given flow rate that must be provided to prevent breakdown of the desired two-phase flow regime. These minimum heater powers expressed in terms of heater exit quality are indicated by the curve of FIG. 2. A system with the above-described heating

60 element has been operated at liquid nitrogen flow rates of up to 5.5 lbs./hr. and at cooling loads estimated at 20 watts.

70 Obviously many modifications and variations of the present invention are possible in the light of the above teachings. It is therefore to be understood that within the scope of the appended claim the invention may be practiced otherwise than as specifically described.

We claim:

A flexible-transfer-tube cryogenic cooling system comprising, in combination:

- an insulated supply vessel having an exhaust port and tubing extending therefrom said vessel being adapted to form a container for the coolant of said cryogenic system, said tubing being fabricated from a material having a high coefficient of thermal conductivity; an insulated load vessel;
- a flexible transfer tube coupling said exhaust-port tubing to said load vessel;
- tubing connecting said load and supply vessels and constituting a return path for said coolant between said vessels;
- pressure means for circulating the coolant of said system at a predetermined mass rate of flow and for regulating the pressure in the system;
- said pressure means including an absolute pressure regulator valve disposed in said return path tubing

5

and a pressure build-up coil disposed in said return path tubing intermediate said regulator valve and said supply vessel;

a solenoid valve disposed in said return path tubing intermediate said coil and said supply vessel; and a heater element enclosing said exhaust-port tubing of said supply vessel, said heater element being of sufficient capacity to provide the minimum heater exit quality relative to the mass flow rate of the coolant required to keep the temperature of said flexible transfer tube above critical temperature.
